UNITED STATES PATENT OFFICE.

GEORGE STINEBRING, OF SHREVE, OHIO, ASSIGNOR TO G. B. LEWIS COMPANY, A CORPORATION OF WISCONSIN.

WAX PRESS.

Application filed July 11, 1921. Serial No. 483,875.

To all whom it may concern:

Be it known that I, GEORGE STINEBRING, a citizen of the United States, and resident of Shreve, in the county of Wayne and State of Ohio, have invented certain new and useful Improvements in Wax Presses; and I do hereby declare that the following is a full, clear, and exact description thereof.

My invention has for its object to provide 10 a simple, economical, durable and effective press for expressing the wax from old honey-combs, generally comprising "capping."

Another object of my invention is to provide a press for the above purpose, wherein 15 the various parts can be readily assembled and dismounted.

A further object of my invention is to provide a construction which will withstand strain, and, at the same time, such construction 20 is developed to materially reduce the cost of manufacture.

With the above and other minor objects in view the invention consists in certain peculiarities of construction and combination of 25 parts as are hereinafter set forth with reference to the accompanying drawings and subsequently claimed.

In the drawings,

Figure 1 represents an elevation of a wax 30 press embodying the features of my invention, with parts broken away and other parts in section to more clearly illustrate the details of construction.

Figure 2, a fragmentary face view showing 35 a tank bale for confining a press spindle cross bar.

Figure 3, a detailed sectional view of an 40 extension ear constituting part of a basket, together with means for suspending it in position, and

Figure 4, a detailed cross section of an 45 overflowing tank spout.

Referring by characters to the drawings, 1 represents an open mouth fluid tank, having 45 a suitably reinforced upper edge, adjacent to which edge there is secured a pair of swinging bales 2. The bales are provided for confining the ends of a cross bar 3, which cross bar is thereby rendered removable. 50 The cross bar is provided with companion slots 4 and a centrally disposed aperture 5, through which aperture there is fitted a screw spindle 6. The screw spindle is in threaded engagement with a correspond-

ingly threaded thimble 7, which thimble is 55 secured to the cross bar by suitable screws 7'. The outer end of the screw spindle has fitted thereto, an actuating arm 6', and the lower end of said spindle has loosely mounted thereon, a skeleton press head 8. The 60 skeleton head 8 is adapted to fit within a cylindrical basket 9, the walls and bottom of which are preferably formed from stout wire meshed cloth. The wire meshed cloth is suitably reinforced at its bottom and top 65 by metallic bands 10—10', whereby the structure, as a whole, is rendered durable and rigid. The basket is further reinforced against end strain by a strap having a bottom stretch 11 and side stretches 11'. The 70 side stretches are secured by rivets, or the like, to the bands 10 and 10'. The side stretches extend beyond the mouth of the basket and are extended to form ears 12, which ears are apertured for engagement 75 with locking keys 13, having downturned ends that straddle the cross bar 3, it being understood that the strap ears 12 are fitted through the slots 4 of said cross bars when the parts are in their working position. 80 The basket is also provided with a second reinforcing strap 14, which is positioned at a right angle to the first mentioned reinforcing strap, and is similar thereto, with the exception that the ear extensions are dispensed with. 85

As best shown in Figures 1 and 4, the fluid tank near its upper edge on the mouth is provided with an overflow spout 15, whereby wax expressed from the cone is discharged into a suitable receptacle. 90

From the foregoing description, it will be seen that a simple and economical wax press is produced which solves the problem of presses for the purpose mentioned, and 95 which press can be readily dismantled and assembled.

In the operation of the press, the usual practice is to insert a bulk of the uncapped comb and scraps of bees wax into the basket, 100 which bulk is preferably encased in a burlap sack or analogous porous jacket. The press head is then positioned over the bulk and the mass is subjected to a bath of hot water contained in the tank of sufficient temperature to melt the wax. As the process of melting proceeds, the screw spindle is turned down so as to express the wax from the bulk 105

and water is added to the container from time to time, whereby the wax which is expressed from the bulk, will rise to the surface of the water and will thereafter run off with the overflow through the spout 15 to a suitable container.

I claim:

In a wax press comprising a cylindrical fluid-tank, having an overflow spout near its 10 upper edge, and companion bales in pivoted union with the side walls thereof near said upper edge; the combination of a removable slotted cross bar adapted to rest upon the upper edge of said tank and engage the 15 bales, a screw threaded thimble secured to the cross bar, a circular basket positioned within the tank, a reinforcing strap extend-

ing across the bottom of the basket and upwardly against the side wall thereof, the strap being formed with apertured ear extensions that are fitted through the cross bar slots, locking keys mounted in the ear apertures engageable with the top surface of the aforesaid cross bar, whereby the basket is held in suspension, and a screw spindle engaging the cross bar thimble, and a skeleton head carried by the lower end of said spindle and adapted to force a comb against the bottom of said basket.

In testimony that I claim the foregoing I have hereunto set my hand at Shreve, in the county of Wayne and State of Ohio.

GEORGE STINEBRING.
